UNITED STATES PATENT OFFICE.

JAMES LEWTAS AND ERNEST HENRY BLACKHURST, OF PRESTON, ENGLAND, AS
SIGNORS TO THE WHITTAKER LOOM COMPANY, LIMITED, OF PRESTON, LANCASTER,
ENGLAND.

AUTOMATIC WEFT-REPLENISHING MECHANISM FOR LOOMS.

Application filed June 18, 1923. Serial No. 646,206.

To all whom it may concern:

Be it known that we, JAMES LEWTAS and ERNEST HENRY BLACKHURST, both subjects of the King of Great Britain and Ireland, 5 and both residing at Yard Works, Stanley Street, Preston, in the county of Lancaster, England, have invented certain new and useful Improvements Relating to Automatic Weft-Replenishing Mechanism for Looms, 10 of which the following is a specification.

This invention relates to automatic weft replenishing mechanism for looms for weaving of the kind in which a feeler is provided for bringing into operation the weft 15 replenishing mechanism, said feeler being adapted to enter an aperture in the shuttle box as the latter moves forward with the lay and so contact with the cop of yarn in the shuttle and to be moved thereby a gradually 20 decreasing amount as the yarn becomes more and more used but sufficient to maintain the weft replenishing mechanism out of action until at a predetermined degree of exhaustion of the yarn the movement of the feeler is insufficient for the 25 above purpose and the weft replenishing mechanism comes into operation.

The object of the present invention is to devise improvements in connection with 30 automatic weft replenishing mechanism of the above character and the invention consists in the combination in automatic weft replenishing looms of the kind referred to of a rod or like member movable with the 35 weft fork hammer and adapted to actuate the weft replenishing mechanism and a feeler adapted to allow of co-operation between the rod and the weft replenishing mechanism.

40 The invention also consists in other details hereinafter pointed out in the claims.

The accompanying drawings illustrate one mode of carrying out the invention:—

45 Figures 1 and 1^a show a plan illustrating one convenient arrangement of apparatus in accordance with the invention, the line A—B representing the inner edge of the breast beam of the loom;

Figure 2 is a side view on a somewhat 50 larger scale of a detail shown in Figure 1;

Figures 3, 4 and 5 are respectively a front elevation, side elevation and plan of a safety device to prevent the operation of the weft-replenishing mechanism in the event of the 55 shuttle failing to enter the shuttle box;

Figure 6 shows in plan view a detail of a modification hereinafter referred to.

Referring to the accompanying drawings, a indicates a loom shuttle containing a purn or spindle b upon which the weft is normally situated, the limiting peripheral lines of the cop being indicated by the broken lines in Figure 1; c is a known feeler device which is shown capable of longitudinal motion against a spring c¹ which normally tends to keep the feeler c in its innermost position (that is, towards the shuttle) and pivoted to said feeler device is a bell-crank lever d pivoted at d¹ on a bracket on the loom framing or breast beam and connected at d² with a rod or like member e engaging the usual weft fork hammer f provided in conjunction with the weft fork g forming the usual weft stop mechanism. Adjacent the end of the rod e is an arm or lever h rigidly secured upon a shaft or spindle i which is mounted in substantially parallel relationship with the line A—B and upon which is arranged a lever k adapted to co-operate with a pin or projection l secured to what is known as the swivel of the automatic weft replenishing mechanism. The swivel is mounted on the shaft of the trans-ferrer which acts to push a full cop from the magazine into the shuttle when the weft 85 is to be replenished and is formed with a pin or projection which, when the swivel is rotated as above described, is brought into the path of a bunter on the lay and the swivel is thereby rotated and the weft 90 replenishing mechanism is actuated.

From the above description it will be seen that during the normal operation of the loom the usual to-and-fro movement of the weft fork hammer f will impart a like movement 95 to the free end of the rod or like member e.

The relative positions and movements of the parts so far described are such that prior to beat up of the weft at the fell of the cloth the feeler c is moved to its innermost position by the spring c¹ which presses upon a collar attached to the shank of the feeler or is otherwise suitably arranged for the purpose. In such position the outer end of the rod or like member e projects across the path of the arm or lever h but as the lay approaches the breast beam during the beat up, the cop of yarn in the shuttle comes into contact with the feeler c and moves the same against the action of the spring, c¹, in such 110

a manner as to move the rod or like member *e* to the left as viewed in Figure 1 so that when the rod or member is moved by the weft fork hammer into the position shown by the dotted lines in Figure 1 the rod *e* does not engage the arm or lever *h* and the latter is therefore unaffected by the movement of the member *e*.

It will be evident, however, that as the 10 yarn is gradually exhausted in the shuttle the amount of movement of the feeler *c* will become less and less until at a predetermined degree of exhaustion of the feeler the movement will not be sufficient to move the 15 member *e* out of the path of the arm or lever *h* so that the latter will be rocked by the forward movement of the member *e* thus rocking the shaft *i* and causing the lever *k* to engage the pin *l* in such a manner as to 20 operate the weft replenishing mechanism in the manner above described to introduce a fresh cop into the shuttle to take the place of that which has become exhausted.

The arm or lever *h* is made of considerable 25 area as is indicated in Figure 2 so that when the free end of the member *e* is not in the requisite position for engaging with the edge of the member *h* there is no danger of any accidental engagement since any longitudinal 30 movement of *e* will then result in its free end striking the broad face of the member *h*.

Since the operation of the weft replenishing mechanism is due to an insufficient amount of movement given to the feeler *c* it will be 35 evident that means must be provided for preventing the operation of the weft replenishing mechanism in the event of the shuttle failing to enter the shuttle box since in the absence of such safety device the feeler 40 in the circumstances referred to would not be moved to the extent necessary to maintain the weft replenishing mechanism out of action. Figures 3 to 5 therefore illustrate a form of 45 safety device which is provided in accordance with the invention and in which *m* is a member slidably mounted in a supporting bracket *n* attached to a part of the loom framing, the member *m* carrying or being formed with an inclined or wedge shaped 50 part *o* adapted to bear against a depending lever *p* which in the form shown is of hook formation and which is pivoted at *p*¹ upon the bracket *n* and is controlled by the spring *p*².

55 The shaft *i* is provided with a fixed projection *q* somewhat inclined as shown in Figure 3. The arrangement is such that if the shuttle fails to enter the shuttle box the nose or some part of the shuttle engages 60 and operates the sliding member *m* thus moving the member *p* into the position shown dotted in Figure 4 so that the end of the member *p* engages the projection *q* in such a manner as to move the same round 65 slightly in a counter-clockwise direction in

Figure 3, the result being that the shaft *i* is also somewhat rotated and the arm or lever *h* is thereby moved more across the path of the member *e* and thus the weft replenishing mechanism is prevented from being operated.

Means may be provided for locking the parts when the starting lever of the loom is moved into position for stopping the loom; thus in Figure 6 (see also Figure 1) the 75 member *r* rigidly projecting from the member *e* is capable of being engaged by a two-armed lever *s t* when the starting lever *u* is in the position for stopping the loom.

With the lever *s t* pivoted at *v* at or about 80 the breast beam of the loom, and *s* being connected to a spring *w* attached at *w*¹ to said beam it is obvious that on the movement of *u* in the direction of the arrow line for starting the loom the lever arm *s* will 85 be pulled away from engagement with the member *r* thus allowing the member *r* and with it the member *e* to move in the manner required for the operation of the parts.

Claims:

1. In an automatic weft replenishing loom of the kind described, the combination with a weft fork hammer and a weft replenishing mechanism actuating element, of a rod like member movable with and extending 90 through said hammer and adapted to actuate the element when the yarn has been exhausted to a predetermined point, and a feeler connected to said rod like member and adapted to allow the actuation of the 95 weft replenishing mechanism element by said member.

2. In a mechanism of the kind described, a feeler adapted to engage the yarn on a 100 shuttle, a spring for normally forcing the said feeler in one direction, a bell crank lever connected to said feeler and actuated by the latter, a rod like member connected to said bell crank lever, a weft fork hammer connected to and actuating said rod like 105 member, a shaft, an arm mounted on said shaft and adapted to be engaged by said rod like member, and a weft replenishing mechanism actuating member connected to said shaft and adapted to be moved by the latter 110 when the arm is actuated by said rod like member.

3. A mechanism as claimed in claim 2 in which the arm has a relatively broad surface arranged in a plane perpendicular to the axis of said shaft and adapted to act as an abutment to engage the end of the rod like member, for preventing the latter from actuating the arm until the rod like member 115 is in proper position to engage said arm.

In testimony whereof we have signed our names to this specification.

JAMES LEWTAS.

ERNEST HENRY BLACKHURST.
